UNITED STATES PATENT OFFICE.

DAVID S. KENNEDY, OF BROOKLYN, NEW YORK, ASSIGNOR TO MERGEN-THALER LINOTYPE COMPANY, A CORPORATION OF NEW YORK.

LINOTYPE-MACHINE.

No. 796,843.

Specification of Letters Patent.

Patented Aug. 8, 1905.

Application filed December 24, 1904. Serial No. 238,185.

To all whom it may concern:

Be it known that I, DAVID S. KENNEDY, of Brooklyn, county of Kings, and State of New York, have invented a new and useful Improvement in Linotype-Machines, of which the following is a specification.

This invention has reference to an improvement in the keyboard mechanism used in the commercial linotype-machine of the present day, and represented in Letters Patent of the United States to P. T. Dodge, No. 530,931, the object of the invention being to insure speedy action of the parts under all conditions.

It consists in a spring attachment for depressing the yokes or levers in which the keyboard-cams are carried, the device being applicable to machines already in use without requiring any alteration therein.

Referring to the drawings, Figures 1 and 2 represent vertical cross-sections from front to rear through the keyboard mechanism with my improvements applied, the figures showing, respectively, the parts in different positions. Fig. 3 is a perspective view of the end of one of the yokes with a spring applied thereto.

Referring to the drawings, A represents the main frame, and B one of the vertically-reciprocating reeds or bars urged constantly downward by a spring C and requiring to be lifted in order that its upper end may actuate one of the magazine-escapements to release the matrices one at a time.

D is a vertically-vibrating yoke or arm mounted at one end on a horizontal pivot *d* and serving to lift the reed B.

E represents an eccentric mounted in a slotted yoke on a transverse pivot *e*. This cam is peripherally grooved and provided with a transverse pin *e'*, which bears normally against a fixed stop-pin *a* on the frame, whereby the cam is for the time being prevented from turning forward in the direction of the arrow, as it has a tendency to do, because of the preponderance of weight on one side.

F is a constantly-rotating rubber-covered roll extending transversely across the entire keyboard and under the corresponding number of cams E.

G is an angular dog mounted on a horizontal pivot *g* and arranged to engage at its upper extremity beneath one end of the yoke D in order to maintain the same in the position

shown in Fig. 1 with the cam E clear of the roll F and its pin *e'* against the stop-pin *a*.

H is a vertically-sliding bar mounted in the main frame, its upper end engaging the dog G and its lower end engaging the finger-key I, pivoted at *i*.

The parts stand normally in the positions shown in Fig. 1, the roll F in motion and the other parts at rest. When the finger-key is actuated, the bar H throws the upper end of the dog G out from under the yoke, which thereupon falls to the position shown in Fig. 2, carrying cam E downward with it. The effect of this action is to carry the pin *e'* clear of the stop, so that the cam is free to turn forward, while at the same time it is permitted to bear upon and frictionally engage the roll. The rotation of the roll imparts motion to the cam E, which for the time being sustains the yoke. Owing to the eccentricity of the cam, its rotation while bearing on the roll has the effect of lifting the yoke above its original level, so that it in turn lifts the reed B and effects the release of the matrix. During this action the dog G resumes its original position and arrests the yoke at its original level, the cam being at the same time arrested and held by the stop-pin *a*.

The construction and operation of the foregoing parts so far as described are the same as in the standard linotype-machine. In practice it is occasionally found that through the fouling of the parts or from other causes due to neglect the yoke D fails to fall and begin its action with the speed required to meet the demands of very rapid operators. To overcome this difficulty, I provide a spring K, adapted to be secured to the cam-yoke D near its pivot. This spring extends downward and bears at its lower extremity against the fixed bar *a'* of the frame, its effect being to urge the free end of the cam-yoke downward, so that the cam falls with great rapidity when the yoke is released from the dog G. This spring may be variously formed; but I prefer to construct it, as shown in the drawings, of a single piece of metal, having a narrow depending spring-arm and the upper portion bent into triangular form and adapted to be projected through the end of the yoke and sprung around the same in the manner shown in the several figures. A spring thus formed may be instantly snapped into place, and being in position it retains a firm hold on the

yoke, the strain tending to keep it in place rather than to displace it.

It is to be observed that in my structure the spring K is interposed between the yoke and a stationary or resisting part of the frame, so that the spring acts directly to effect the depression of the yoke and the consequent fall of the cam to its operative position.

A spring applied to depress the yoke carrying the cam, as in the present organization, serves not only to insure the descent of the yoke promptly, but also to insure an instantaneous and firm engagement between the cam and the underlying driving-roll. In practice it is found that when the rolls become smooth or burnished on the surface there is sometimes a hesitation on the part of the cam and consequent delay in the delivery of the matrix from the magazine. This trouble is eliminated by the employment of the spring.

Having thus described my invention, what I claim is—

1. In a keyboard mechanism of the class herein shown, the combination of a movable

yoke D, and the cam therein, an underlying roll, and a spring acting to move the yoke toward the roll, whereby the prompt and positive engagement of the cam with the roll is insured.

2. In a keyboard mechanism of the type herein shown, the cam-carrying yoke, D, in combination with the depressing-spring, K, secured to the yoke near its pivot and bearing on a rigid support.

3. For use in a keyboard of the type herein shown, a slotted cam-yoke, D, having a spring, K, secured thereto.

4. As a member of a keyboard mechanism, a slotted cam-carrying yoke, D, having a spring, K, bent around one end of the same and held by its own elasticity.

In testimony whereof I hereunto set my hand, this 22d day of December, 1904, in the presence of two attesting witnesses.

DAVID S. KENNEDY.
